W. R. BEAZLEY.
ELECTRODE HOLDER.
APPLICATION FILED JULY 21, 1920.

1,376,185.

Patented Apr. 26, 1921.

FIG. 1.

FIG. 2.

By *Willie Maguire* Attorneys

UNITED STATES PATENT OFFICE.

WILLIAM RICHARD BEAZLEY, OF JACKSONVILLE, FLORIDA.

ELECTRODE-HOLDER.

1,376,185.

Specification of Letters Patent. Patented Apr. 26, 1921.

Application filed July 21, 1920. Serial No. 397,918.

To all whom it may concern:

Be it known that I, WILLIAM RICHARD BEAZLEY, of Jacksonville, in the county of Duval and State of Florida, have invented 5 certain new and useful Improvements in Electrode-Holders; and I do hereby declare the following to be a full, clear, and exact description of the invention, such as will enable others skilled in the art to which it appertains to make and use the same.

10 My object is to provide improved means for removing the connector straps of a battery by an electric current, thus avoiding the necessity for drilling the straps. For 15 this purpose I provide a simple and inexpensive electrode holder capable of ready adjustment.

In the drawing, Figure 1 is a side elevation of the entire mechanism. Fig. 2 is a 20 plan of one of the electrode holders.

I have shown a pair of carbon electrodes 1 mounted in two holders 2. These holders consist of a pair of plates 3 having sleeves 4 near their edges to receive the carbons 1. 25 An asbestos bushing 5 is set in each of the sleeves to directly contact with the carbon electrodes. By means of porcelain tipped set screws 6 the electrodes are held adjusted in the desired positions.

30 Each of the plates 3 is rabbeted as at 7 to receive the other plate and they are slotted, as at 8. A bolt 9 extends through the slots in the upper plate. This bolt is threaded 35 at its lower end to receive a wing nut 12. By loosening the nut the plates may be moved relatively to each other to separate the two electrodes to the desired extent.

Depending from the bolt 9 is a chain or 40 wire 13 which carries a pair of tongs 14 having toothed jaws 15. A spring 16 tends to hold the jaws open.

The device is equipped with an upright 45 rod 17 secured to the upper plate 3. This rod is provided with an asbestos shield 18

and its outer extremity constitutes a handle 19. The handle is formed with an outer grip portion 20 preferably of wood and lined with asbestos.

From a source of electric energy 21 the 50 conductor wires 22 supply current of low voltage (six to twenty four volts) to the electrodes. The wires are shown passing through the handle and connected with the electrodes by copper clamps 23.

When the electrodes are placed on the lead connector straps the circuit is completed and the resistance of the carbon causes the electrodes to quickly attain a white heat. By pressing upon the handle 60 the electrodes melt the connector straps. The tongs 14 are secured to the battery plates or the jars or covers and as the device is quickly jerked away the plates or other parts will be withdrawn from the battery. 65 By means of the adjustable features the device may be used on any make of battery. I provide a range of adjustment of the electrodes from one and a half to seven inches so that they may readily correspond 70 to the positions of the cell posts.

I claim as my invention:

1. An electrode holder comprising a pair of plates formed with registering slots, an electrode carried by each of said plates, a 75 bolt passed through said slots, and a nut on said bolt.

2. An electrode holder comprising a pair of plates, an electrode carried by each of said plates, said plates being rabbeted and 80 formed with registering slots, a bolt passed through said slots, and a nut on said bolt.

3. An electrode holder comprising a pair of relatively adjustable electrode supporting plates, and a pair of tongs carried by said 85 holder.

In testimony whereof I have signed this specification.

WILLIAM RICHARD BEAZLEY.
